Attorney.

UNITED STATES PATENT OFFICE.

DAVID S. FULLER, OF CHICAGO, ILLINOIS, ASSIGNOR OF ONE-HALF TO
WATTS DE GOYER, OF CHICAGO, ILLINOIS.

GOOSE-CALL.

SPECIFICATION forming part of Letters Patent No. 726,277, dated April 28, 1903.

Application filed January 2, 1903. Serial No. 137,503. (No model.)

To all whom it may concern.

Be it known that I, DAVID S. FULLER, a citizen of the United States, residing at Chicago, in the county of Cook and State of Illinois, have invented certain new and useful Improvements in Goose-Calls; and I do hereby declare the following to be a full, clear, and exact description of the invention, such as will enable others skilled in the art to which it appertains to make and use the same.

My invention relates to a novel construction in a goose-call, the object being to provide a device of this character which is readily adjustable to vary the tones produced to imitate either a male or female goose or a duck and which is very simple, durable, and efficient; and it consists in the features of construction and combinations of parts hereinafter fully described and claimed.

The accompanying drawing, illustrating my invention, shows my goose-call in central longitudinal section.

My said device consists of a mouthpiece member A and a call member B, removably secured therein. The said member A consists of a cylindrical sleeve of fanciful form on its outer surface, which is provided at its rear end with a metallic ferrule C, provided with a tongue D, extending toward the mouth end and preferably inlaid in the outer face of said sleeve. Passing through the end portion of said tongue D and radially through the wall of the sleeve A is a small internally-screw-threaded sleeve E, of a soft metal, provided at one end with an external annular flange F and its other end adapted to be overturned to form a flange G, whereby said sleeve E is held firmly in place. Said sleeve E is adapted to receive a set-screw H, having a pivoted thumb-piece I, the function of which will be hereinafter described. The said call member B consists of a slightly-tapered block one end of which is practically cylindrical, as at J, and the other end of which is practically semicylindrical, as at K, said cylindrical portion J being of considerably less length than the semicylindrical portion K and provided with central opening L, which is extended into the semicylindrical portion K in the shape of a practically semicylindrical groove M, extending to a point adjacent the

end of said block, being gradually enlarged toward said end. Loosely mounted on said portion K of said block and abutting against the portion J at its larger end is a practically semicylindrical but slightly tapered block N, between which and said portion K of said member B the ends of two reeds O and P are clamped, said reeds being preferably of different thicknesses of sheet metal, the reed O being bent to extend upwardly at an incline from the inner end of the block N and having its free end bent downwardly, as at Q, while the reed P lies flat upon the portion K of said member B on each side of said groove M and has its free end bent slightly upward, so as to give it freedom to vibrate, there being a very small space between the end of the reed P and the upper face of said portion K of the member B to permit passage of the air through said groove M and opening L. In operation the said reeds O and P and the block N are placed in position on the portion K of the member B and said portion K, with said reeds and block N, inserted into the member A until said block N is wedged firmly therein, thus firmly clamping the reeds in place and holding said member B firmly in place in said member A. The said reed O now projects into the path of said set-screw H, which is brought to bear on same to adjust it to produce variations in its vibration. By now blowing into the mouth end of said member A the said reeds O and P are vibrated and produce the hoarse discordant tones common to geese, ducks, and other aquatic birds. By adjusting the screw H many variations of tones are produced; but these variations are capable of further modification by varying the position of the block N with reference to the ends of said reeds and likewise varying the distance to which said member B projects into the member A, thereby varying the point at which the screw H bears upon the reed O, all of which will obviously change the vibrations of said reeds and alter the tones produced.

My said device is very simple and efficient, easily adjusted, and produces sounds exactly imitating those of aquatic birds in particular.

I claim as my invention—

1. A goose-call or the like comprising in combination a mouthpiece member consisting

of a sleeve, a radially-adjustable set-screw therein, and a telescopic call member adapted to be inserted into one end of said mouthpiece member, reeds carried by said call member and projecting into the path of said set-screw, and a wedge interposed between said mouthpiece member and said call member to secure the latter removably in place.

2. In a goose-call or the like, the combination with a call member consisting of a tapered block cut away at one end, a groove in said cut-away portion, and reeds mounted over said groove, of a mouthpiece member adapted to receive said call member at one end, and devices carried by said call member and engaged by said mouthpiece member to clamp said reeds in place and hold said call member removably in place in said mouthpiece member.

3. In a goose-call, the combination with a tubular mouthpiece member, of a tapered call member adapted to project telescopically into said mouthpiece member at one end, a longitudinal groove in said call member, reeds interposed above said groove, and a wedge interposed above said reeds, said wedge being adapted to partially enter said mouthpiece member and be engaged by the walls thereof to bear upon and clamp said reeds in place and hold said call member removably in place in said mouthpiece member, substantially as described.

4. In a goose-call, the combination with a tubular mouthpiece member, of a tapered call

member adapted to project into said mouthpiece member at one end, a longitudinal groove in said call member, reeds interposed above said groove, and a wedge interposed above said reeds, said wedge being adapted to partially enter said mouthpiece member and be engaged by the walls thereof to bear upon and clamp said reeds in place and hold said call member removably in place in said mouthpiece member, and devices carried by said mouthpiece member and adapted to engage one of the reeds of said call member to vary the position thereof, whereby the tone produced is varied, substantially as described.

5. In a goose-call, the combination with a tubular mouthpiece member, and a radial set-screw therein, of a call member comprising a block adapted to enter said mouthpiece member, a longitudinal groove in said block, reeds projecting over said groove, and devices bearing on said reeds and engaging the walls of said mouthpiece member to clamp said reeds in place and hold said call member removably in place in said mouthpiece member, said reeds being adapted to project into the path of and be engaged by said set-screw to alter the tone produced, substantially as described.

In testimony whereof I affix my signature in presence of two witnesses.

DAVID S. FULLER.
